UNITED STATES PATENT OFFICE

ROSS C. CAMPBELL, OF SPRINGFIELD, ILLINOIS

FRAME-CLAMP SUPPORT FOR ORNAMENTAL AWNING FIXTURES

Application filed September 24, 1926. Serial No. 137,501.

My invention relates to devices adapted to be used for supporting ornamental awning fixtures on the extension frame members of a porch, window awnings, and the like.

5 An object of my invention is to provide a substantial, neat appearing and economically manufactured supporting clamp for the support of ornamental spear heads and the like on the corners of awning frames at the elbow where the awning frame arm is bent at right angles for the support of the awning fabric.

10 A particular object of my invention is to provide in a device of this character a neat and quickly applied frame clamp support for ornamental awning fixtures which may be merely clamped or cleated onto the elbow of the bent awning frame in order to provide a detachable mounting for spear heads and 15 other suitable decorative ornamental fixtures for awnings.

15 I attain the objects of my invention in the device described in the annexed specification, recited in the claim and illustrated in the 20 accompanying drawings, in which like reference numerals indicate like parts in the several figures.

25 Referring to the figures:

Figure 1 is a perspective of my invention 30 shown by itself.

Figure 2 is a side view of the device of my invention shown clamped to an awning arm so as to engage an elbow by means of the integral cleats on the device of my invention. 35 This view also shows attached to my ornamental fixture support a spear head of suitable type showing the manner in which the device of my invention is adapted to support the ornamental spear heads.

40 Figure 3 is a perspective of a portion of an awning showing how an awning would look with ornamental fixtures supported by the device of my invention.

Figure 4 is an end view of the device of my 45 invention shown clamped about an awning frame member and supporting an ornamental awning fixture.

50 Referring in detail to the drawings, I shall now point out the merits of my invention and the method of applying and using the same.

Heretofore when ornamental awning fixtures have been mounted on an awning frame such fixtures as spear heads and the like have been secured to plates or attached by means of T-joints and the like necessitating the use 55 of awning arms composed of several units connected to the T-joint or to the plate and when so constructed provide an opportunity for the joints to work loose and for the awning to sag and cause trouble; but in my frame clamp support for ornamental awning fixtures, I provide a device which may be used 60 successfully with an awning arm of one piece bent at the corners forming a U-shaped frame member to which the device may be 65 quickly attached by merely clamping the cleats of my device over the elbow or corners of the U-shaped frame member; an operation which requires very little time to do and which is very easy to do and when mounted 70 my device looks neat in appearance and provides a substantial and practical means of 75 supporting ornamental awning fixtures on an awning frame member.

In detail, I provide a mounting member 75 —1— provided with threads and the like for detachably receiving and supporting spear heads —2— or other suitable ornamental 80 detachable awning fixtures. Integral with mounting member —1— is a body member —3— provided with a quarter circular channel —4— having a shape adapted to admit of the device being secured to the elbow —5— or corner of an awning frame member of the 85 type where the frame member is made into a U-shaped member all of one piece.

When my mounting bracket is secured to elbow —5— it is adapted to be mounted so as to permit cleats —6— and —6'— and —7— 90 and —7'— to be quickly and easily bent to clamp about arms —8— and —9— respectively of the U-shaped awning frame member.

It will be seen by studying the drawings 95 that when cleats —6— and —6'— are substantially clamped about arm —8— and cleats —7— and —7'— substantially clamped about horizontal arm —9—, both arms being integral, these cleats are thus clamped on integral right angularly disposed arms. The 100

device of my invention engages the elbow —5— formed by integral arms —8— and —9—. My bracket will thus be securely held into operative position for the substantial detachable support of spear head awning fixtures and the like without weakening the awning frame by having to make T-joints and the like at the corners for the detachable support of ornamental awning fixtures.

10 It will be seen by those who are skilled in the art of awning manufacture that a U-shaped awning frame member is always more solid and substantial when it is made in one piece with the corners bent rather than with the corners connected by joints of other types of connections and it will be readily understood by those who are accustomed to mounting ornamental awning fixtures that a great deal of time may be saved when mounting a support for such ornamental fixtures if the bracket for their support may be merely clamped on the corner of the awning frame by cleats such as —6—, —6'—, —7— and —7'— which are relatively so disposed as to be able to hold the bracket of my invention snugly and securely to the corners of the frame as is shown in the drawings.

When the device of my invention is in normal use, it is adapted to be so mounted as to avoid interferences with the awning fabric —10— and in fact, may be used in connection with the so-called California type of awning on porches, windows and the like and always look neat and artistic and provide an unusually substantial mounting for an ornamental awning fixture while at the same time, it provides a mounting that is economical to manufacture and install.

40 To those skilled in the art to which this device pertains, it will be evident that certain little details of construction of my device may be changed without departing from the spirit and scope of my invention. For instance, the mounting member —1— may be provided with a threaded socket or provided with other suitable means of detachably securing spear heads —2— and the like to the bracket on the mounting member —1—. The preferred arrangement, however, is illustrated in the 45 drawings and has been hereinabove described.

Having thus described the nature of my invention, what I claim is:

55 A frame clamp support for ornamental awning fixtures, comprising in integral combination a metallic quarter circular bracket formed to provide a rounded elbow clamp for a bent awning frame; said bracket of semi-circular cross section and having sides 60 forming a channel for engaging said frame; said channel sides extended adjacent the ends so as to provide pliable cleat members for engaging the bracket to the frame, and said bracket further provided with an integral 65 protruding body member having a threaded

recess for receiving and engaging an awning fixture.

In witness whereof, I hereunto set my hand this 2nd day of September, A. D. 1926.
